UNITED STATES PATENT OFFICE.

HUGH MISCAMPBELL, OF DULUTH, MINNESOTA.

DUST COLLECTOR.

Application filed December 7, 1925. Serial No. 73,628.

This invention relates to dust collectors and has particular reference to such a device for application to a lime hydrator.

In the hydration of lime intense heat is created resulting in a large proportion of the lighter and finer particles of lime being carried off by the draft in the stack of the hydrator, and it is the principal object of this invention to prevent the escape of these valuable products during the hydration process.

Other minor objects and advantages of the invention will appear in the further description thereof.

Referring now to the accompanying drawing, forming part of this application, and in which like reference characters indicate like parts:

Figure 1 is a side elevation of the dust collector, partly broken away and partly shown in section, as applied to a lime hydrator;

Figure 2 is an enlarged fragmental sectional view of the horizontal spray pipe; and

Figure 3 is a cross sectional view of the spray pipe showing the spray nozzle.

The hydrator is diagrammatically shown at 1, it having the cone shaped cap 2 directly thereover which forms the base of the stack in which the dust collector is housed. In ordinary installations it is the usual practice to have the hydrator properly placed on a lower floor of the building, and the stack 3 extend from the hydrator up through the next adjacent upper floor where it is turned horizontally for a short distance as at 4, and then again turned to a vertical as at 5 and on out through the building to the atmosphere; it being obvious that the steam, gases, and other products resulting from the hydrating process, pass out through this stack.

My improved dust collector is preferably installed within this horizontal section 4 of the stack and the same consists of the axially disposed hollow water supply pipe 6, which is supported within said section in any desired manner, as for example by the journals 7, each of which is supplied with an oil pipe 8, accessible from the exterior of the stack. Spaced equi-distant longitudinally of the pipe 6 are a plurality of vertically disposed pipes 9, they being hollow and communicating with the interior of the pipe 6. At the extreme end of each of these pipes 9 is fixed a spray nozzle such as illustrated at

10, it being provided with the adjusting screw 11 for regulating the spray and the set screw 12 for holding the screw 11 in any desired set position. A fan 13 is also mounted upon the pipe 6 which may be used for the purpose of creating additional draft within the stack, or retarding the natural draft therein, depending upon which way the blades of the fan are turned. The shaft 60 or pipe 6 passes out through a dust and water tight packing 14 and into the adjacent water supply tank 15, the intake to said tank being shown at 16, and a discharge for draining the tank when necessary at 17 controlled by the valve 18. There is also a shut off valve shown at 19 in the pipe 6 adjacent the tank 15 so that water from the tank may be prevented from entering the pipe 6 when desired. Upon the shaft 6 is installed the 70 pulley 20, about which is the belt 21 to and about the pulley 22 of the motor 23 for supplying power and rotating the shaft 6.

The horizontal section 4 of the stack is preferably corrugated as clearly illustrated 80 and in the bottom of each corrugation is drilled a relatively small hole 24.

Thus when the tank 15 is filled with water and the valve 19 opened, the water will flow longitudinally of the shaft 6 through the 85 pipes 9, and in the form of a spray out through the nozzles 10, the same making a cloud of mist within the horizontal corrugated section of stack 4. If there is not enough pressure in the tank 15 to cause the 90 spray nozzles to properly function, the motor 23 may be caused to operate thus revolving the shaft 6 and nozzles at any desired predetermined speed as circumstances may require thereby causing the water to be forced 95 out the nozzles at the required pressure by centrifugal force. Consequently when, during the hydrating process, the finer and more valuable particles of the lime are carried up the stack by the draft, they must traverse 100 this cloud of mist resulting in their being precipitated and falling to the bottom of the section 4 of the stack and running out with the water through the holes 24 and falling into the tank 25 installed in any desired manner directly therebelow. In one extreme end of this tank 25 there is fixed the pipe 26 which communicates with the sprinkler 27 within the hydrator 1. In the other end of the tank 25 there is the overflow 105 discharge pipe 28 but this does not function until the level of the water and precipitated

products in the tank is above the upper end of the transverse baffle 29 installed adjacent the pipe 28. It is thus obvious that the products rising from the hydrator through 5 the stack are caught by the dust collector and returned to the hydrator with the water for initially hydrating the lime.

I have also shown at 30 an obliquely disposed baffle secured within the stack 5 to 10 further retard the dust in its attempt to pass out of the stack with the draft, and at 31 there is illustrated a dust tight door through which access may be had to the interior of the stack for any desired purpose.

15 From the foregoing it is evident that I have produced an efficient and practical dust collector for hydrating or other machines, and it is obvious that various modifications may be resorted to without departing from 20 the spirit of the invention.

Having thus described one embodiment of my invention what I claim and desire to secure by Letters Patent is:

1. In combination a dust discharging stack 25 having an offset therein, the offset portions of said stack being connected by a circum-

ferentially corrugated, horizontally disposed, section of pipe, a hollow shaft suspended within said horizontal section having radially disposed arms discharging directly 30 against the inner surface of said corrugations, one end of said shaft extending outboard of the stack, means for rotating the shaft, and means for supplying water under pressure thereto.

35 2. The combination with an offset dust discharging stack of the character described having a horizontal section connecting the offset portions, of a hollow water conducting shaft mounted within said horizontal section and extending outboard of the stack for connection with operating mechanism, and means mounted upon the shaft for spraying the water directly against the inner surface of the horizontal section, and means carried 40 by the shaft for regulating the draft through the horizontal section for the purpose described.

45 In testimony whereof I hereunto affix my signature.

HUGH MISCAMPBELL.
